UNITED STATES PATENT OFFICE.

CHARLES R. GETHER, OF MILWAUKEE, WISCONSIN.

PUNCHING-MACHINE.

No. 893,069.

Specification of Letters Patent. Patented July 14, 1908.

Application filed September 30, 1907. Serial No. 395,073.

To all whom it may concern:

Be it known that I, CHARLES R. GETHER, a citizen of the United States, residing at Milwaukee, county of Milwaukee and State of Wisconsin, have invented new and useful Improvements in Punching-Machines, of which the following is a specification.

My invention relates to improvements in that class of punching machines which are used for perforating the marginal edges of sheets of paper preparatory to being connected together by the modern so-called loose leaf binder, and it pertains more especially among other things, first, to the mechanism by which a plurality of punches are adjustably connected with and simultaneously operated by a single revoluble punch operating shaft, and second to the means employed for communicating a vertical reciprocating motion from the operating agency to the punch operating shaft.

The construction of my invention is explained by reference to the accompanying drawings, in which,

Figure 1 is a front view of a machine. Fig. 2 is a vertical sectional view drawn on vertically dotted line of Fig. 1. Fig. 3 is a detail showing a modified form of device for operating the machine by foot power.

Like parts are identified by the same reference characters throughout the several views.

2 represents the punch actuating shaft which is revolvably supported at its respective ends in journal bearings 3 formed integrally with the supporting frame 4. The shaft 2 is provided upon one side with a longitudinal flange 5 which is adapted to engage in transverse grooves 6 formed near the upper ends of the several punch shanks 7.

8 represents the punch guides which are provided with a vertical aperture for the reception of the punch shanks 7. The several punch guides 8 are connected with a die plate 9 which is permanently secured thereto by screws or rivets in the ordinary manner and each punch guide is also provided with a gage 10 which is slidably supported in an aperture provided therein and secured at any desirable point of adjustment by the hand screw 11.

The punch guides 8, die plates 9, and gages 10 are all of the ordinary construction. When such parts are connected together as shown in Fig. 2, they are rigidly secured at any desirable point of adjustment to the supporting

bar 12, by the hand actuated bolts 13. The bar 12 is provided with a longitudinal slot 14 for the reception of the hand actuated bolts 13. The die plates 9 of each set are adapted to rest upon the upper surface of the bed plate 15, and said bed plate is supported from the frame 15'. 16 is a longitudinal slot formed in the bed plate. Thus it is obvious that by releasing the hand bolt 13, the punch guide together with the punches, die plates and other connecting parts are adapted to be adjusted longitudinally of the slot 16, whereby a greater or less number of punches and dies may be used at a time and such parts 70 may be adjusted nearer to or farther from each other as the various kinds of work to be performed may require, while owing to the fact that the shanks 7 are connected with the operating shaft 2 by a longitudinal flange 5, 75 operating in the groove 6, the punch dies and parts rigidly connected therewith may be readily and quickly adjusted longitudinally of the operating shaft, it being necessary when desirous to change the adjustment of 80 such parts to simply turn back the hand bolt 13 until the desired adjustment is made when they are again secured in place by turning down said hand screw 13 against the retaining bar 12.

When desirous to operate the punches by foot power, the shaft 2 is connected with an operating pedal 16 by pivotal bolt 17, link 18, pivotal bolt 19 and lever 20, which lever 20 is rigidly affixed to one side of said shaft 2. 90

21 represents a spring by which the pedal 16 is connected with a stationary part of the machine not shown.

In operating the device, the punch is forced downwardly by the downward pressure of the pedal 16 while the spring 21 is expanded, when by releasing the pressure on the pedal, the pedal is moved in the opposite direction by the recoil of said spring, whereby the punch is raised and withdrawn from 100 the paper.

By the preferred form of operating mechanism shown in Fig. 2, motion is communicated from the power driven pulley 22 to the punch actuating shaft 2 through the pulley 105 supporting shaft 23 eccentric 24 (which is rigidly affixed to said shaft 23,) collar 25, link 26, pivotal bolt 27, lever 28, segmental gear 29 and segmental gear 30. The segmental gear 29 is formed integrally with or 110 connected to the lever 28. The segmental gear 30 is formed integrally with or con-

nected to the shaft 2. It will be obvious that with each revolution of the pulley 22, a vertically reciprocating movement will be communicated therefrom to the several 5 punches through the several parts named.

For convenience of description the punch, die plate, punch shank and guide, which are all rigidly connected and adapted to be moved together are hereinafter referred to 10 as punch and die sets.

Having thus described my invention what I claim as new and desire to secure by Letters Patent is,

1. In a machine of the class described, the 15 combination of a revolute punch actuating shaft, a longitudinal flange affixed to and projecting radially from the periphery of said shaft, a plurality of punch and die sets, the punch shanks of which are respectively provided 20 with transverse grooves for the reception of said longitudinal flange upon which they are adapted to be longitudinally adjusted, means for adjustably connecting the several punch and die sets together above a suitable die supporting bed plate, a die supporting 25 bed plate, an operating lever and means for communicating motion from said lever to said revolute punch actuating shaft.

2. In a machine of the class described, the 30 combination of a revolute punch actuating shaft, a longitudinal flange connected with the periphery of said shaft, a plurality of punch and die sets, the punch shanks of which are respectively provided with trans- 35 verse grooves adapted to be adjustably connected with said longitudinal flange, means for adjustably connecting the several punch and die sets together above a suitable die supporting bed plate, a die supporting bed

plate, a frame for supporting said bed plate, a revolute power driven shaft supported from said frame, a driving pulley supported on said shaft, an operating lever connected with said punch actuating shaft, means for communicating motion from said power driven shaft to said lever and means for communicating motion from said lever to said revolute punch actuating shaft.

3. In a punch machine of the described class, the combination of a revolute punch actuating shaft a longitudinal flange projecting from the periphery of said shaft, of a plurality of punch and die sets, the punch shanks of which are respectively provided with transverse grooves for the reception of the longitudinal flange of the punch actuating shaft, means for adjustably connecting the several punch and die sets together above a suitable die supporting bed plate in adjustable connection with said actuating shaft, a die supporting bed plate, a frame for supporting said bed plate, a revolute power driven shaft supported from said frame, a driving pulley supported on said shaft, an eccentric rigidly connected to said shaft, a collar slidably connected to said eccentric, an operating lever connected with said punch actuating shaft, means for communicating motion from said eccentric and inclosing collar to said lever, and means for communicating motion from said lever to said punch actuating shaft.

In testimony whereof I affix my signature in the presence of two witnesses.

CHARLES R. GETHER.
